US00D733106S

(12) **United States Design Patent**
Frei et al.

(10) **Patent No.:** **US D733,106 S**
(b4) **Date of Patent:** **** Jun. 30, 2015**

(54) **SENSOR COMMUNICATION DEVICE WITH WALL MOUNT**

(75) Inventors: **Randall W. Frei**, San Jose, CA (US);
Linker Cheng, San Jose, CA (US);
Robert J. Pera, San Jose, CA (US)

(73) Assignee: **UBIQUITI NETWORKS, INC.**, San Jose, CA (US)

(**) Term: **14 Years**

(21) Appl. No.: **29/425,966**

(22) Filed: **Jun. 28, 2012**

(51) **LOC (10) Cl.** **14-02**

(52) **U.S. Cl.**

USPC **D14/240**

(57) **CLAIM**

The ornamental design for a sensor communication device with wall mount, as shown and described.

DESCRIPTION

FIG. 1 presents a perspective view of a sensor communication device coupled with a wall mount.

FIG. 2 presents a perspective view of the sensor communication device to be coupled with the wall mount.

FIG. 3 presents a front view of the sensor communication device; and,

FIG. 4 presents a front view of the wall mount.

1 Claim, 4 Drawing Sheets
